UNITED STATES PATENT OFFICE.

ABRAHAM MATTINGLY, OF OWENSBOROUGH, KENTUCKY.

MASH-MACHINE.

SPECIFICATION forming part of Letters Patent No. 241,045, dated May 3, 1881.

Application filed December 6, 1880. (No model.)

To all whom it may concern:

Be it known that I, ABRAHAM MATTINGLY, a citizen of the United States, residing at Owensborough, in the county of Daviess and State of

5 Kentucky, have invented certain new and useful Improvements in Mash-Machines; and I do hereby declare the following to be a full, clear, and exact description of the invention, such as will enable others skilled in the art to 10 which it appertains to make and use the same, reference being had to the accompanying drawings, and to the letters or figures of reference marked thereon, which form a part of this specification.

15 This invention relates to certain improvements in mechanisms for stirring mash in mash-tubs; and it has for its objects to provide an improved stirrer, whereby the mash will be more expeditiously and effectively agitated 20 than heretofore, and to provide a means for conveniently elevating the stirrers out of the tub, when desired, at the expense of but little time and labor. These objects I attain by the mechanism illustrated in the accompanying 25 drawings, in which—

Figure 1 represents a vertical sectional view, showing my apparatus applied to a mash-tub; and Fig. 2, a front elevation with a portion broken away.

30 The letter A indicates a mash-tub of the ordinary description, and B the frame-work carrying the stirring mechanism.

The letter C indicates a vertical shaft, carrying a rotary stirrer, D, at its lower end; and 35 E a tubular sleeve mounted on said shaft and resting upon a shoulder, F, near its lower end. The said sleeve carries at its lower end a stirrer, G, and at its upper end is journaled in bearings H, secured to the frame B. The shaft 40 C projects above the upper end of the sleeve E, and is provided at its upper extremity with a swivel, I, from which extends a rope or chain over the pulleys J, mounted in hangers secured to the upper part of the frame B, the free end 45 of the said rope or chain being provided with a counter-balance, K, for the purpose herein-after explained. The shaft and its sleeve are provided with fast miter-gear wheels L M, which gear with a miter-gear wheel, N, on opposite sides of the same, the said gear-wheel N being mounted on a horizontal shaft, O, 50 mounted in bearings P, and capable of a lon-

gitudinal movement therein. The said shaft is provided with fast and loose pulleys Q R, for the reception of a band from a suitable driving-wheel.

The letter S indicates a lever, pivoted at its upper end to the frame B, and extending downward within convenient reach. Said lever is connected with the horizontal shaft at T, so 60 that said shaft can be conveniently moved horizontally, in order to throw the gear-wheel into or out of gear with the wheels L M.

The letter U indicates two stops, for holding the lever in either position to which it may be 65 shifted.

The stirrers D and G consist each of a series of inclined radial blades, secured, respectively, to the vertical shaft and sleeve, and provided on the sides facing each other with a series of 70 vertical blades, as shown. These stirrers are adapted to rotate in opposite directions, the vertical blades of one stirrer being arranged to pass those of the other during rotation.

The letter V indicates the cover of the mash-tub, provided with a hopper, W, through which it may be charged.

X indicates a collar on the shaft, above the cover, by means of which the cover may be elevated with the stirring mechanism.

The letter Y indicates a pivoted bar, by means of which the cover may be secured to the tub by means of suitable hooks secured to the tub on opposite sides, whereby the cover is prevented from turning when the shaft is 85 rotated.

The operation of my invention will be readily understood in connection with the above description, and is as follows: The gear-wheels, being properly arranged to intermesh with 90 each other, upon imparting motion to the horizontal shaft, will cause the stirrers to rotate in opposite directions and thoroughly agitate the mash. When the stirring is completed, to elevate the stirring mechanism it is only 95 necessary to throw the gear-wheel N out of gear by means of the mechanism before mentioned, when the vertical shaft and its sleeve, carrying the stirrers, will be readily raised, owing to the counter-balance above described.

Having thus fully described my invention, what I claim, and desire to secure by Letters Patent, is—

1. The rotary stirrers provided with inclined

radial blades having vertical blades on their facing sides, as described, and adapted to travel in opposite directions, substantially as specified.

- 5 2. The combination, with the rotary stirrers provided with inclined radial blades having vertical blades on their facing sides, as described, and the vertical shaft and sleeve, carrying said stirrers, and mounted in vertical 10 bearings, of the swivel at the upper end of the vertical shaft, connected with a rope passing over pulleys, and provided with a counter-balance, substantially as specified.
3. In combination with the counterbalanced

shaft and sleeve carrying the stirrers, and provided with miter-gear wheels, the miter-gear wheel mounted on an adjustable horizontal shaft, whereby the said wheel may be thrown into or out of gear with the wheels on the shaft and sleeve, substantially as and for the purposes set forth. 15 20

In testimony whereof I affix my signature in presence of two witnesses.

ABRAHAM MATTINGLY.
